UNITED STATES PATENT OFFICE

ULYSSES J. SMITH, OF CLEVELAND, OHIO

DESIGN FOR A BURIAL CLOISTER

Application filed September 26, 1931. Serial No. 41,239. Term of patent 3½ years.

To all whom it may concern:

Be it known that I, ULYSSES J. SMITH, a citizen of the United States, residing at Cleveland, in the county of Cuyahoga and State of Ohio, have invented a new, original, and ornamental Design for a Burial Cloister, of which the following is a specification, reference being had to the accompanying drawings, forming part thereof.

Fig. 1 is a perspective view of the burial cloister, showing my new design.

Fig. 2 is a top plan view thereof on a reduced scale.

I claim:

The ornamental design for a burial cloister, as shown.

ULYSSES J. SMITH.
